FEED DEVICE FOR THE INKING-RIBBONS OF WRITING-MACHINES.

No. 833,561.

Specification of Letters Patent.

Patented Oct. 16, 1906.

Application filed November 11, 1904. Serial No. 232,885.

To all whom it may concern:

Be it known that we, ADOLF STEINER, engineer, and ROBERT REIN, mechanical engineer, residing at Berlin, in the German Empire, have invented certain new and useful Improvements Relating to Feed Devices for the Inking-Ribbon of Writing-Machines, of which the following is a specification.

This invention has for its object means for feeding the inking-ribbon in writing-machines in which the two vertical spindles carrying the inking-ribbon spools are each provided with a ratchet-wheel, with which engage pawls rocking in horizontal planes, while the inking-ribbon spindles rotating in horizontal planes feed the inking-ribbon lying in a vertical plane. Further, in the machines of the kind here under consideration by the displacement of an adjustable bar the ratchet-wheels are thrown into or out of gear by means of pawl mechanisms which are alternately oppositely set, this displaceable part being arranged between the rocking lever and the ratchet-wheels.

In accordance with this invention our improvement consists in the fact that the inking-ribbon spools are arranged separately from the adjusting-bar and that the two pillars carrying the inking-ribbon spools are independent of the adjusting-bar. The operating means are provided with operating-pawls rocking upon the spindle of the ratchet-wheels, by which means, as compared with the known arrangement in which operating levers or pawls rocking in a plane tangential to the ratchet-wheels are employed, a more reliable feed is obtained. As in this novel arrangement the pillars are not displaceably arranged they are necessarily stronger and more rigid, so that the ribbon-spools are better supported. The adjusting-bar, which alone is displaced in this case, is more readily displaceable, as it is not weighted by the pillars. The operating-levers rocking in a vertical plane act upon a disk rocking around the spindle of the inking-ribbon spools, which disk carries the operating-pawls, and the positive reversal of the operating mechanism is effected by disks which are rotatable around the spindle and are connected with the common operating-slide.

The novel inking-ribbon-operating device is illustrated in the accompanying drawings by way of example.

Figure 1 shows the adjusting-bar with the two operating devices in plan. Fig. 2 represents an operating device in front elevation and in section. Fig. 3 shows the driving mechanism for the operating device in side elevation, parts being in section; and Fig. 4 represents a sectional detail on the line A A of Fig. 3 as viewed in the direction indicated by the arrow x. Fig. 5 is a plan view of the adjusting-bar.

The two operating devices are driven by means of a rocking yoke 74, which in the known manner upon the depression of a key-lever is caused to rock and which may also serve for the displacement of the paper-roller in the known manner. The yoke 74 carries the two operating-levers 80, both of which constantly rock with it, but which become operative alternately. The two inking-ribbon spools 93 are carried by the sleeves 92, which are passed upon pillars 95. These latter are attached to the frame of the machine by standards 99 at their lower part. Consequently the two pillars 95 95 may serve to guide the operating-bar 100. This may advantageously be effected in such a manner, as shown in Fig. 1, that the slide 100 is arranged longitudinally displaceable on one of these pillars 95 with a slot 101, arranged in a lateral lug 101'. The other end 85 of the bar 100 is pivoted on a disk 104, further description of which will follow. The construction of the bar 100 is shown in Fig. 5. The two operating-pawls 102 are mounted on levers 103, which rock around the pillars 95 90 or around the sleeves 92 in a horizontal plane. The rocking movement of the levers 103 is produced by the operating-lever 80, previously referred to and which is connected with the yoke 74. Both levers 103 constantly participate in the oscillations of the yoke 74. Only one of these levers 103 is, however, in engagement at one time, owing to the fact that by the displacement of the slide 100 to one side or the other one of the two pawls 102 is maintained out of engagement with the ratchet-wheels 94 by means of a device hereinafter described.

As shown in Figs. 1 and 4, in addition to

the operating-pawls 102 locking-pawls 103' are also provided. These pawls 103' are pivoted on stationary levers 111, fastened to the standards 99 of the frame; and are also 5 adapted to engage with the ratchet-wheels 94 in order to prevent any automatic retractive rotation of the inking-ribbon spools during the return movement of the pawls 102. These locking-pawls 103' must be disengaged 10 at the same time as the pawls 102, in order that the displacement of the ribbon may take place. This common release of the operating-pawls 102 and of the locking-pawls 103' is preferably produced by means of rotary disks 104, which carry the two fingers 15 105 and 106. The alternate engagement and disengagement of the two operating devices takes place in the example here illustrated by means of the slide 100—say in such 20 a manner that the slide at 107 and 108 acts upon the two disks 104, so that these are positively displaced together in the same direction.

In the position represented in Fig. 1 the slide occupies its extreme left-hand place. In this position the fingers 105 106 have lifted the two pawls 102 103' on the left-hand side, while the same pawls on the right-hand side are situated in the operative position. The inking-ribbon is then wound onto the ribbon-spool on the right hand of Fig. 1. The reverse is the case when the slide is displaced opposite to the direction indicated by the arrow to the other side.

The device described above may of course vary considerably in its details. The essential point is that in any case the inking-ribbon spools no longer require adjustment and that the two operating devices are positively set in an opposite manner by means of the operating member 100, so that one operating

device is always engaged and the other is always disengaged.

Having now particularly described and ascertained the nature of our said invention 45 and in what manner the same is to be performed, we declare that what we claim is—

1. In a writing-machine, the combination with the machine-frame, of separated vertical spindles rigidly supported thereon, ribbon-spools rotatable about the spindles, ratchet-wheels carried by the spools, levers oscillating about the spindles, and pawls pivoted upon the levers and coöperating with the ratchet-wheels. 55

2. In a writing-machine, the combination with the machine-frame, of two separated vertical spindles rigidly supported thereon, ribbon-spools rotatable about the spindles, ratchet-wheels carried by the spools, operating-pawl and locking-pawl engaging the ratchet-wheels and levers oscillating about the spindles and having arms extending at different angles therefrom and contacting with the pawls. 65

3. A feed device for inking-ribbons comprising a spindle, a spool rotatable about the spindle, a ratchet-wheel carried by the spool, a pawl mounted to oscillate about said spindle, operating means movable about the spindle and contacting with the pawl, and a member for moving the operating means having a slot to receive the spindle. 70

In witness whereof we have hereunto signed our names, this 28th day of October, 1904, in the presence of two subscribing witnesses.

ADOLF STEINER.
ROBERT REIN.
